Jean G. Theobald, Meriden, Conn., assignor to
International Silver Company, Meriden, Conn.,
a corporation of New Jersey

Application November 30, 1939, Serial No. 88,586

Term of patent 14 years

To all whom it may concern:

Be it known that I, Jean G. Theobald, a citizen of the United States, residing at Meriden, county of New Haven, State of Connecticut, have invented a new, original, and ornamental Design for a Tray or Other Article of Hollow Ware, of which the following is a specification, reference being had to the accompanying drawing, forming a part thereof.

Fig. 1 is a top plan view of a tray showing my design, it being understood that the outer border is continued around the entire circumference of the tray and that the inner ornamentation is

continued around the entire circumference of the bottom of the tray; and

Fig. 2 is a fragmentary view of the bottom ornamentation only, on an enlarged scale, for the purpose of bringing out the details of the design.

The design is here shown as applied to a tray, but it is also intended for use on sets comprising various articles of hollow ware for table use.

I claim:

The ornamental design for a tray or other article of hollow ware, substantially as shown and described.

JEAN G. THEOBALD.
